13 Claims. (Cl. 242—80)

1

This invention relates to apparatus for coiling and cutting a continuously moving web and particularly to the coiling of a web of wire mesh fabric known as poultry netting and, in particular, to an apparatus for progressively forming such material into tight, centerless coils and disposing of them at a rate sufficient to keep pace with the production of the machines on which the fabric is made by twisting separate strands of wire together.

Machines for making wire mesh of the type mentioned have been improved so that the material can be turned out at speeds as high as 180' per minute. This material is usually sold in coils or rolls containing 150'. Apparatus for coiling the material has not been correspondingly improved so as to enable it to keep pace with the production now obtainable on the fabric-making machines. If it is attempted to dispose of the material by winding it on a mandrel, then cutting off the proper length, removing the coil and starting the material on an empty mandrel, the time required for these operations is so great that it is necessary to stop the machine for each coil with consequent loss of production and increase in cost. I have invented a method and apparatus for forming a tight coil of netting without the use of a mandrel, shearing the material, starting a new coil in a region spaced from the first coil, and discharging the first coil while the succeeding coil is being formed. This makes possible the continuous coiling of the output of a poultry-netting machine without shutdowns for removing a coil and starting a new one.

In a preferred embodiment and practice of my invention, I provide two sets of bending rolls and coil-supporting rollers mounted in spaced coiling regions. I also provide a double-acting shear cooperating with a deflector to divert the leading end of the web issuing from the machine alternately toward one and then the other of the sets of bending rolls. The bending rolls serve to make the web self-coiling as it is fed to the supporting rollers. I also provide coil-holding means and coil throw-out means for removing the coils from the supporting rollers when completed, as well as an automatic control system for actuating the shear, coil-holding and throw-out means when a predetermined length of material has been coiled.

A complete understanding of the invention may be obtained from the following detailed description and explanation which refer to the accompanying drawings illustrating the present preferred embodiment. In the drawings:

2

Figure 1 is a side elevation with parts omitted showing the coiling apparatus and a runout conveyor adjacent thereto for disposing of coils as formed;

5 Figure 2 is a side elevation of the coiling apparatus alone;

Figure 3 is a partial section taken along the plane of line III—III of Figure 2;

10 Figure 4 is a central vertical section through the coiler;

Figure 5 is a diagram illustrating the automatic control system; and

15 Figure 6 is a side elevation showing the side of the machine opposite that shown in Figure 2.

10 Referring now in detail to the drawings and, for the present, to Figure 1, the apparatus of my invention comprises a pair of spaced side plates 10 supported on a suitable base 11 and connected adjacent their upper ends by tie rods 12. The side plates have upper and lower coiling tables 13 and 14 pivoted thereon. A continuous web of poultry netting 15 is fed into one side of the machine between entry guide rolls 16 from any suitable type of machine for making this material.

20 The entering web then passes between a pair of driven pinch rolls 17 and through a shear 18. Depending on the position of the shear, it engages one side or the other of a deflector 19 from which it is guided toward one of the tables 13 and 14. Further details of these parts of the machine will be described later by reference to Figures 2 through 4. Coils formed on the tables 13 and 14 are loosely held thereon by retaining members 20 and 21 and when completed, are ejected by throw-out members 22 and 23 which normally lie below the level of the tables.

25 Coils delivered from the upper table 13 slide down skids 24 and are guided onto a conveyor 25 by curved arms 26. Coils formed on the lower table are delivered directly to the conveyor by skids 27. The conveyor consists of an endless belt traversing spaced pulleys and supporting rollers, the belt being driven by one of the pulleys, and serves to move the coils of netting longitudinally for storage or shipment.

30 Referring now more particularly to Figure 4, the entering guide rolls 16 are journaled in brackets 28 secured to the edges of the side plates. The web entering between these guide rolls next passes between guides 29 mounted on the inner faces of the side plates 10 by cross rods 30 extending therebetween. The pinch rolls 17 feed the web through the shear and bending rolls to be described later. The upper pinch roll

35 is journaled in bearings fixed in the side plates

10. The lower pinch roll is journaled in floating bearings mounted on levers 31 pivoted to the side plates at 32. Bearings 33 have adjusting screws 34 engaging the levers 31 to control the pressure exerted by the pinch rolls on the web.

The shear 18 comprises a gate member or head 35 extending between the side plates 10 and having a longitudinal slot 35a therethrough adapted to admit the web 15. The gate is slideable vertically in guides 36. A hydraulic cylinder 37 has its piston rod connected to the gate for actuating it upwardly and downwardly. The gate has cutting blades 38 secured thereto adjacent the upper and lower edges of the slot therethrough. These blades cooperate with a fixed blade 39 mounted in the deflector 19. The sides of the deflector adjacent the blade 39 slope upwardly and downwardly to change the course of the web after a shearing operation resulting from vertical movement of the gate 35 in either direction. That is to say, if the gate is in its upper position and the web is being fed to the upper coiling table 13, downward movement of the gate causes severance of the web by the upper blade 38 and the fixed blade 39 and simultaneously shifts the web to the lower face of the deflector which immediately guides the leading edge of the oncoming web toward the lower coiling table 14.

Upper and lower idle guide rolls 40 are journaled in the side plates adjacent the sloping faces of the deflector 19. An upper guide chute 41 conducts the web between secondary pinch rolls 42, one of which is journaled in fixed bearings and the other on pivoted lever arms, in the manner similar to the mounting of the lower pinch roll 17. A guide chute 43 conducts the web from the pinch rolls 42 to a cluster of three bending rolls 44. These rolls include a small roll engaging the faces of two larger rolls so that the web passing therebetween is bent to a curvature having the radius of the small roll and is thereby made self-coiling. After the web passes through the bending rolls, it forms a tight, centerless coil on the table 13 which will be described in greater detail shortly.

When the gate 35 is in its lower position, as previously described, the web is diverted toward the lower table 14 by the deflector 19. It passes over the lower idle guide roll 40 through a guide chute 45 and between secondary pinch rolls 46 similar to those shown at 42. The web then passes through a guide chute 47 around idle guide rolls 48 and between tertiary pinch rolls 49, also similar to those shown at 42. From the pinch rolls 49, the web passes through a guide chute 50 to a cluster of bending rolls 51 similar to that shown at 44. These rolls also serve progressively to bend the web to the radius of the small roll, thereby causing it to be self-coiling, whereby a tight, centerless coil is built up on the lower table 14.

The coiling tables 13 and 14 are substantially identical so only one of them will be described in detail. The table 13 comprises driven rollers 52 lying in a substantially horizontal plane and idle rollers 53 lying in a substantially vertical plane. The rollers 52 are journaled in side plates 10. The rollers 53 are journaled in brackets 54 secured to the edges of the side plates. The coil-retaining member 20 cooperates with the rollers 52 and 53 loosely to confine the coil of netting formed as the web emerges from the bending rolls 44. The retaining members 20 and 21 are substantially identical and the details of their construction are shown in Figure 3. Each com-

prises a pair of arms 55 connected by a tube 56 which is fixed on a shaft 57 journaled in the side plates 10. Idle rollers 58 are journaled in bearing bars 59 pivoted on a shaft 60 secured to the outer ends of the arms 55. Coil springs 61 exert a clockwise torque on the bars 59 to hold the rollers 58 in a predetermined position relative to the arms 55 which position is determined by suitable stops (not shown). The pivoted frame 10 composed of the arms 55, tubes 56 and rollers 58 is counterbalanced by a weight 62 secured to the tube. A crank arm 63 on the shaft 57 permits the member 20 to be swung into and out of coil-retaining position by suitable operating mechanism to be described later.

The ejectors or throw-out members 22 and 23 are substantially identical. Each comprises a frame including side plates 64 connected by cross members pivoted on a cross shaft 65. The innermost cross member designated 66 is concave and is adapted to lie below a coil confined between rollers 52, 53 and 58 as it is being formed. When a coil is completed, it may be ejected by tilting movement of the throw-out member. Each shaft 65 is provided with a crank 67 for effecting such movement. As the inner end of the ejector rises, the finished coil is cradled on the cross member 66 and, when the ejector has been sufficiently tilted, the coil rolls downwardly therefrom onto the skids 24 or 27, as the case may be.

The bending rolls and the several sets of pinch rolls are driven by a motor 68 and a reducing gear 68a. A sprocket 69 on the reducing gear drives a chain 70 trained around sprockets on the various driven rolls and suitable idler sprockets as shown in Figure 6. The sprockets on the various driven members are designated by corresponding reference numerals with a prime affixed. The various idler sprockets are designated 71.

Hydraulic cylinders 72 and 73 mounted on one of the side plates 10 operate the cranks 63 and 67 of the upper and lower coil-retaining members 20 and 21 and ejectors 22 and 23. The cylinder 72 has a piston adapted to engage a bell crank 74 and cause counterclockwise angular movement thereof. A link 75 is pivotally connected to the crank 63 of the upper retaining member 20 and to one arm of the crank 74. A link 76 is pivotally connected to the crank 67 of the upper ejector 22 and another arm of the crank 74. The cylinder 73 has a piston adapted to engage a bell crank 77 similarly connected by links 75' and 76' to the cranks 63 and 67 of the lower retaining member 21 and ejector 23. The cranks 74 and 77 are journaled on pivot pins secured to one of the side plates.

Figure 5 illustrates an automatic control system for the hydraulic cylinders 37, 72 and 73. The cylinder 37 is supplied by a pump 78 and the cylinders 72 and 73 by a pump 78'. These pumps are driven by a motor 79 and draw oil from a tank 80 on which the pumps and motor are mounted. The pump 78 delivers oil through a high-pressure line 81 to a 4-way electromagnetic valve 82 controlling the cylinder 37. The pump 78' similarly delivers oil through a high-pressure line 81' to 4-way electromagnetic valves 83 and 84 for controlling the cylinders 72 and 73, respectively. The valves 82, 83 and 84 are of known construction and include a reciprocable piston actuated in opposite directions by solenoids on opposite sides of the valve to connect the ends of a hydraulic cylinder alternately to a pressure

source and a return pipe 80' connected to the tank 80.

Successive operations of the control system to actuate the shear gate 35, one of the coil-retaining members and ejectors are initiated by a 2-way switch 85 actuated by a counter 92 driven by the pinch rolls 41. This counter is adapted to cause the moving contact of the switch 85 to shift from one to the other of two fixed contacts, after a predetermined number of revolutions of the pinch rolls indicating the passage therebetween of a predetermined length of web. With the shear gate in the upper position as shown in Figures 4 and 5, the incoming web is formed into a coil between the upper rollers 52 and 53. As the coil builds up, the retaining member 20 moves clockwise through a small angle. This causes slight tilting of the ejector 22 but the movement of the latter is not sufficient to cause the cross member 66 to engage the coil. When the desired length of web has been formed into a coil, the counter operates the switch 85 from the solid-line position to the dotted-line position. This completes a circuit from one side of a power source (designated by a plus sign within a circle) through the switch 85, the left-hand solenoid of valve 82 and a limit switch 86 to the other side of the supply circuit (indicated by a minus sign within a circle). The resulting energization of the valve solenoid causes the valve piston to move to the left and establish communication between the line 81 and the pipe connection to the upper end of the cylinder 37. The shear gate 35 is thus actuated downwardly to sever the web and divert the severed end of the incoming material toward the lower coiling table. The trailing end of the coil on the upper table is wound up as the coil continues to rotate under the driving torque applied by the rolls 52.

As the shear gate 35 descends, limit switch 86 is opened by a finger 86a on the gate. This de-energizes the left-hand solenoid of the valve 82. The descent of the gate also closes a switch 87 by engagement therewith of an operating finger 87a on the gate. The switch 87 closes a circuit from one side of the supply line through the switch, and the right-hand solenoid of valve 83 to the other side of the supply line. The piston of valve 83 is thereby operated to connect the high-pressure line 81' to the pipe connected to the bottom of the cylinder 12. The piston of cylinder 12 is then operated to actuate the bell crank 14. This lifts the upper retaining member 20 and tilts the upper ejector 22 to discharge the coil formed thereon. The switch 87 is of such type as to close the circuit for the right-hand solenoid of valve 83 instantaneously and then reopen it. The operation of the bell crank 14 closes a switch 88 which energizes the left-hand solenoid of valve 83. The piston in cylinder 12 is thus forced downwardly and the retaining member 20 and ejector 22 are restored to their lowermost positions. The return of the crank 14 to its starting position opens the switch 88.

When the desired length of the web has been coiled on the lower table 14, the counter restores the switch 85 to the solid-line position. This energizes the right-hand solenoid of valve 82, the circuit being completed through a limit switch 89 which is closed when the shear gate is in its lower position. This operates the valve piston to connect the high-pressure line 81 to the pipe connected to the bottom of the cylinder 37, thus causing upward movement of the gate 35. The web is thus severed and the leading end of the

incoming web is diverted to the upper table. The switch 89 is opened by an actuating finger 89a on the gate, thus deenergizing the solenoid of valve 82.

5 The upward movement of the gate 35 closes a switch 90 by engagement therewith of an actuating finger 90a on the gate. This switch energizes the left-hand solenoid of valve 84 instantaneously and then opens in the same manner as the switch 87. Energization of the left-hand solenoid of valve 84 causes the high-pressure line 81' to be connected to the pipe extending from the valve to the right-hand end of the cylinder 13. This causes the piston of said cylinder to advance and actuate the bell crank 11 in the counterclockwise direction to raise the retaining member 21 and tilt the lower ejector 23 to discharge the coil formed thereon. The movement of the crank 11 actuates a switch 91 to energize 10 the right-hand solenoid of valve 84 and cause retraction of the piston in cylinder 13, returning the retaining member 21 and lower ejector 23 to starting position. Switches 88, 89 and 91 are of the spring-opened type and thus return to open 15 position as soon as their actuating means is retracted.

It will be apparent from the foregoing that my invention is characterized by numerous important advantages over prior methods and apparatus for coiling a web of wire mesh fabric such as poultry netting. In the first place, the provision of two coiling mechanisms in spaced positions, operating alternately, permits the continuous coiling of the web without stopping the machine on which it is made, each time a coil is completed and removed. In other words, substantially the full time required to form a coil of proper length, somewhat less than a minute, is available for binding the previously formed coil 20 and delivering it to the run-out conveyor. I thus avoid interruptions in the operation of the fabric-making machine and I am able to take full advantage of the high operating speed thereof. The progressive bending of the web so that it is 25 self-coiling and tends to form itself into a tight, centerless coil makes it unnecessary to use mandrels and avoids the time and labor necessary for putting them in place and subsequently removing them from the finished coils. The loose confinement 30 of the coils as they are formed on the coiling tables permits them to be quickly discharged when finished. The automatic operation of the coil-retaining members and the tilting ejectors insures that the operations will be conducted in the proper sequence and as quickly as 35 possible. In addition, the construction of the apparatus is simple, so that it may be easily manufactured and operated without substantial maintenance.

40 Although I have illustrated and described only a preferred embodiment and practice of the invention, it will be recognized that changes in the details of construction and procedure may be made without departing from the spirit of the 45 invention or the scope of the appended claims.

I claim:

1. Apparatus for coiling and cutting a continuously moving web comprising a frame, two sets of bending rolls journaled therein, a deflector for directing the web toward one or the other of said sets, and a pair of shear blades extending along the deflector adjacent thereto and movable across the path of the web to sever it and carry the severed leading edge of the web 50 from one side of the deflector to the other.

2. The apparatus as defined by claim 1 characterized by a pair of feed rolls adjacent said blades for continuously advancing the web toward the deflector.
3. The apparatus as defined by claim 1 characterized by a fixed shear blade on said deflector cooperating with said movable blades.
4. The apparatus as defined by claim 1 characterized by said sets of bending rolls being spaced vertically from said deflector.
5. The apparatus as defined by claim 1 characterized by a reciprocable head in which said blades are mounted, and means for actuating said head.
6. The apparatus as defined by claim 1 characterized by a reciprocable head in which said blades are mounted, and a hydraulic cylinder for reciprocating said head.
7. The apparatus as defined by claim 1 characterized by a plurality of rollers adjacent each set of bending rolls for supporting the coil of fabric formed by the latter.
8. The apparatus as defined by claim 7 characterized by retractable coil-restraining means for holding the coil on said supporting rollers as it is being formed.
9. The apparatus as defined by claim 1 characterized by coil throw-out means mounted adjacent each set of bending rolls.
10. The apparatus as defined by claim 1 characterized by means actuated in accordance with the length of web coiled for operating said blades.
11. Apparatus for coiling and cutting a continuously moving web comprising a frame, a set of bending rolls journaled therein effective progressively to form the web into a coil, feed rolls journaled in said frame for feeding the web into the bending rolls, shear means between the feed rolls and bending rolls for severing the web, means for actuating said shear means after a predetermined length of web has been coiled, coil throw-out means and means actuated by operation of the shear for operating said throw-out means.
12. Apparatus for coiling and cutting a continuously moving web comprising a frame, a set of bending rolls journaled therein effective progressively to form the web into a coil, feed rolls journaled in said frame for feeding the web into the bending rolls, shear means between the feed rolls and bending rolls for severing the web, means for actuating said shear means after a predetermined length of web has been coiled, retractable coil-restraining means for loosely confining a coil as it is being formed and means actuated by operation of the shear for operating said coil-restraining means.
13. In an apparatus for coiling and cutting a continuously moving web, the combination with a pair of vertically spaced centerless coilers of a deflector for directing the web toward said coilers alternately and a vertically reciprocating up-cutting and down-cutting shear adjacent said deflector, said shear being effective to sever the web and sweep the leading severed edge from one side of the deflector to the other.
